UNITED STATES PATENT OFFICE.

ULYSSES G. LEE, OF NEW YORK, N. Y., ASSIGNOR TO MONTAGUE MAILING MACHINERY CO., A CORPORATION OF TENNESSEE.

ADDRESSING AND PRINTING MACHINE.

1,014,762.

Specification of Letters Patent. Patented Jan. 16, 1912.

Application filed August 16, 1909. Serial No. 513,044.

To all whom it may concern:

Be it known that I, ULYSSES G. LEE, citizen of the United States, residing at New York, N. Y., have invented certain new and 5 useful Improvements in Addressing and Printing Machines, of which the following is a specification.

My invention is designed to print addresses or to make repeated impressions, as 10 in ordinary printing. I employ printing plates and an impression member or pad, and preferably an interposed inking ribbon. When my invention is embodied in a machine for printing addresses, the printing 15 plates are fed in succession to the printing point beneath the impression member or pad, but when used for printing where repeated impressions of the same form are to be made, the plate feeding mechanism 20 is controlled to permit a plurality of repeated actions of the impression member in connection with the same printing plate.

The invention consists in the features of construction and combination and arrangement of parts hereinafter described and particularly pointed out in the appended claims.

In the accompanying drawings Figure 1 is a front view of a machine embodying my 30 invention; Fig. 1^a is a detail view of a repeating pawl; Fig. 2 is a plan view of the machine with the paper feed mechanism omitted; Fig. 3 is an end view; Figs. 4, 4^a, 4^b, 4^c and 4^d are views of a stacker chute for the printing plates; Fig. 5 is a detail cross 35 sectional view of the guideways for the printing plate and feeding chain, looking from the right of the machine, Fig. 1; Figs. 6, 7, 8 and 9 are views of details relating to the ribbon feed; Fig. 10 is a sectional view 40 of the feed drum for the printing plate feeding mechanism, showing also the controlling ring for repeating; Fig. 11 is a side view of the part shown in Fig. 10; Fig. 12 shows in side and edge view the feeding pawl; Fig. 13 shows in two views the feeding 45 ratchet; Fig. 14 shows in two views the controlling ring for duplicating, triplicating or repeating the impression; Figs. 15, 16 and 17 show respectively a plan, side elevation, 50 and end view of the box or tray for storing the printing plates; Figs. 18, 19, 20 and 20^a are views relating to a friction device for operating the driver of the ribbon reversing mechanism; Figs. 21 and 22 are views relat-

ing to the ribbon reel and the means for 55 driving the same; Fig. 23 is a plan view of the paper feed attachment for the addresser; Fig. 24 is a front view of the same with parts in section; Fig. 25 is a detail view of the main plate or bracket belonging to the 60 feed attachment; Fig. 26 is a view of the ribbon cover plate. Fig. 27 is a view of one of the standards of the hopper or chute arranged at the right of Fig. 1 from which the printing plates are fed by the carrier, 65 the view being taken looking from the right of Fig. 1, and at the inside of the left hand standard, the plate holding tray being shown in position; Fig. 28 is a front view of the standard of Fig. 27, a part of the plate holding tray being indicated in dotted lines with the detent in its retracted position; Fig. 29 is a plan view of the standard of Fig. 27 70 partly in section; Fig. 30 is a view of the right hand standard of the plate feeding 75 hopper or chute looking at the inner side of the same from the left of Fig. 1, a portion of the tray being shown in position. Figs. 31 and 32 show the standard of Fig. 30 in elevation and in sectional plan. 80

The machine is operated from a foot lever 1 connected to a shaft 2, which has fixed thereon a lever 3. This lever forms a part of a toggle joint, the other member 4 of which is pivoted thereto and to a 85 lever 5. This lever 5 is connected with the lower arm of a yoke 6, by means of a bolt 6^a and an interposed spring 6^b. The upper end of the yoke extends over the main frame or table of the machine, and is supported and guided by a link 7 pivoted at 7^a 90 to a bracket on the frame. The overhanging upper arm of the yoke carries the impression pad 8. The lever 5 is pivoted in a suitable bracket of the frame, and has an 95 arm 5' extending forwardly, to which a chain 9 is attached which passes around a pulley 10 Fig. 10. This pulley also has a chain 11 attached thereto in such a manner that it tends to rotate the combined pulleys, 100 and the drum A to which the said pulleys are attached, in an opposite direction from that caused by the downward movement of the chain 9. The chain 11 is attached, at one end, to the pulley 10 within the grooved 105 portion 10', and at its other end it is attached to a spiral spring 12 connected, at its other end, with a suitable part of the frame.

When the foot lever is depressed, the lever 5 is operated, and through the described connections, the drum A is given a half revolution in the direction of the arrow. This drum A to which the pulleys 10, 10' are attached, is mounted loosely on the shaft B. At the same time this action occurs, the yoke 6 is depressed, and this moves directly downward in a substantially vertical line by reason of the combined action of the lever 5 and the link 7, so that the pad 8 will move vertically. The described half revolution of the pulleys 10, 10' and the drum A, sets the drum in proper position for the one step feeding action of the printing plate. The plates are fed by projections D on a chain C, the said chain passing around the chain wheel B² rigid with shaft B and around an idler B³ at the end of the main frame. When the foot lever is depressed, as above described, and the drum A is rotated for half a revolution in the direction of the arrow, Fig. 1, the spring 12 is stretched by means of the pull from the chain 11, and when the foot lever is released, the spring exerts its force to rotate the drum A in the opposite direction, and this motion is communicated to the shaft B for a half revolution by means of a pawl a carried by the drum, Figs. 11 and 12, and a two-toothed ratchet wheel b Figs. 11 and 13, fixed on the shaft B and engaged by the said pawl. These parts constitute elements of a clutch for the printing plate feed. The half revolution of the drum A imparted by the spring 12 and the chain 11 being transmitted to the shaft B through the pawl and ratchet, the printing plate feeding chain C is thereby given a one step movement to remove the printing plate which has just made the impression from beneath the impression pad, and to feed a fresh plate into place thereunder. The plate which is removed falls into a receiving tray carried removably in a stacker chute F, which has a follower G associated therewith, upon which the plates are supported within the stacker chute, and which follower is gradually lowered as the plates are fed into the chute, one lowering action of the follower taking place for each plate fed into the chute. The follower is carried by a screw H, which is driven from the shaft B by beveled gearing g, g', these beveled gears g' being on a transverse shaft I suitably journaled in the frame. The follower block G is connected with the screw H by a pawl J which permits the follower to be quickly raised or lowered by simply throwing the pawl out of engagement with the screw threads, or permits the said follower to be moved down by degrees in accordance with the printing plates as they are fed into the stacker, the follower being lowered just the thickness of a plate at each half revolution. As above stated, the

plates fall into a tray, and this is marked f in the drawings, it being of channel form with a bottom portion and upright side flanges f', and having also catches f² at its ends to retain the plates in place therein. 70 The stacker chute is mounted to swing forwardly on trunnions in order to facilitate the removal of the filled tray without danger of dislodging the printing plates therein. These trunnions are on the same center 75 with the shaft I, so that the stacker chute may be swung without interfering with the proper meshing of the miter gears which drive the adjustable screw H. I employ a catch K to engage a pin k projecting laterally from the stacker chute, so as to hold it in normal vertical position, the said catch having also a shoulder k' to engage the pin k to hold the chute in inclined position when it is desired to move the trayful of plates. 80 The ratchet driving mechanism associated with the drum A and shaft B for giving the plate feeding chain its movements, is arranged so that duplicating or triplicating or repeating of the impressions may be effected by making a simple adjustment which will, for the time being, throw out the feed of the chain so that a plurality of impressions may be made from the same printing plate. For this purpose a ring a² 90 Figs. 10, 11 and 14, is loosely mounted on the pawl carrying drum or wheel A, and the drum A is cut away at the point where the pawl a is located, as shown in dotted lines, Fig. 11, so that a roller on the pawl can 100 engage the inner periphery of the ring. On the periphery of this ring there are two rims or flanges, one of which has two ratchet notches a³, and the other has three notches a⁴. Pawls G' and H' are pivoted to the 105 frame, and are adapted to engage these notches when the proper pawl is thrown into engaging position. When the pawl G' is thrown into engagement, the ring a² will move upon the drum A to the extent of 120° 110 for each impression, so that at every third impression it will rotate back to its starting point, so that the point of the transmitting pawl a is free to operate and engage the tooth of the ratchet wheel b, but at any other point it remains disengaged by reason of its roller a⁵, which engages the inner circumference of the ring a². This ring, on its inner circumference, is cut out at only one point, a⁶, so that, when this portion of the ring has been brought opposite the roller, it allows the pawl to engage the tooth of the ratchet wheel b to transmit the motion to the shaft B and to the plate feeding chain. 115 This engagement of the pawl a causes the rotation of the shaft B at every third impression. When the other pawl H' is thrown into action, the shaft B will move at every second impression. In other words, the drum A carrying the pawl a will oscillate 125 130

idly until such time as the ring a^2 in its step by step movement due to the pawl $G' H'$ brings its cut away part opposite the pawl a , when the latter, no longer held by the intact part of the ring from the ratchet b will engage said ratchet and give a feed movement to the shaft B , and feed chain on the next forward movement of the drum. It will be understood also that the pawl $G' H'$, being mounted on the frame, will displace the ring a^2 in relation to the drum when said drum rotates backward or in a direction opposite to that indicated by the arrow in Fig. 1, and thus the step by step movement is given to the ring.

For making the impressions, I employ a ribbon L extending over the path traversed by the printing plate and beneath the impression pad 8. This ribbon is attached at one end to a ribbon reel 15, Figs. 1, 2 and 21, loosely mounted on a sleeve M , which, in turn, is loosely mounted on a pin supported in the frame. This loose sleeve M is driven from the shaft B through a suitable belt and belt wheels b^2, b^3 , on the shaft B and the sleeve M , respectively. Driving connection is made between the reel 15 and the sleeve M by means of a friction spring 15' carried by the reel, and bearing upon the loose sleeve. The ribbon extends from this reel around a guide pulley Y , and thence to a ribbon spool X fixed to a shaft U , with which is associated ribbon reversing mechanism. This ribbon reversing mechanism also controls the movement and the feed of the ribbon, which is about one-eighth of an inch for each impression. This mechanism comprises an arm N mounted to swing about the axis of the ribbon spool shaft U , and connected by a link O with a portion of the yoke 6, so that movement is imparted to the disk arm N at each action of the yoke, and, consequently, once for each impression. This disk arm carries two pawls, P and Q , pivoted thereto at n , and it has also pivoted at this point a pawl controlling arm R . The pawls P and Q are adapted to engage a ratchet wheel T , which is fastened to the shaft U , and the direction of rotation of the ratchet wheel T , with its shaft U , and, consequently, the ribbon spool X , will depend upon which of the two pawls, P and Q , is in engagement with the toothed wheel T . By means of these pawls such movements may be given to the ribbon spool X as to either wind the ribbon thereupon or unwind it therefrom.

When the predetermined amount of the ribbon, amounting practically to the entire ribbon, has been wound on the spool, the continued action of the feed mechanism described will place extra tension on the ribbon because its end is fastened to the ribbon reel 15, and its intermediate portion, passing over the roller Y , will, under this extra tension, impart movement to the said roller and its carrying lever Y' against the tension of the spring Z . This lever will therefore swing laterally, and its arm Y^2 will be thrown down to depress a reversing stop C' , removing the same from a reversing lever S , which is now allowed to swing about the axis of the shaft U until arrested by a stop S' , said swinging movement being due to a spring D' hereinafter described. In this action of the reversing lever S , its arm S^2 carrying a pin s will cause the shifting of the pawl controlling arm R because of the engagement of the pin s with the forked end of the said controlling lever, and this controlling lever will therefore throw the engaged pawl out of engagement with the toothed wheel T and throw the disengaged pawl into action, so that the movement of the shaft U will now be reversed from that which it formerly had, to unwind the spool and allow the ribbon to unwind step by step therefrom, about one-eighth of an inch at each action. The movement of the lever S is due to a torsional spring D' connected therewith at one end surrounding the shaft, and connected with a friction wheel E' on the said shaft U . This wheel E' is driven from the shaft U by a friction spring e within it, and a friction leather e' . As shown in Figs. 18 and 20^a, the wheel E' has an overhanging flange which receives the friction spring and leather within it. This wheel or casing is mounted loosely on the shaft U . A disk E^x is fixed on the said shaft, and carries a pin e^2 which engages the end of the friction spring and leather, and transmits through their friction contact the rotary movement of the shaft U to the wheel E' . This wheel has also a stop pin e^3 which, when one revolution has been given to the wheel E' and to the torsion spring, will strike against a stop pin e^4 on the hub of the arm S , so that the torsion spring will be wound up sufficiently in this one revolution to have the required power for throwing the arm S when the stop pin C' is moved therefrom, and the torsional action will take place whether the shaft U is moved in one direction or the other. In order to place the main shaft U under a certain amount of resistance, I provide friction washers V, V , on each side of the bearing 16 in which the shaft U is journaled, and I employ a tension spring W to place a pressure on these washers so that they will grip the bearing and hold the shaft firmly against movement, except when the friction is overcome by the action of the driving pawl P or Q carried by the lever N .

Reverting to the action of the ribbon reel 15 in connection with the ribbon movement and reversing mechanism just described, it should be observed that the shaft B rotates one-half of a revolution for each impression, 130

and therefore drives the sleeve M upon which the ribbon reel is loosely mounted once for every impression. The friction spring 15' causes the ribbon reel to rotate 5 sufficiently to take up any slack when the ribbon is moving from right to left, at which time the ribbon spool X is being rotated step by step to unwind the ribbon so that it may pass therefrom and be wound on the 10 reel 15, the action of each movement of the ribbon being about one-eighth of an inch, as above stated. When the ribbon is moved from left to right, the ribbon reel 15 is rotated by the pull of the ribbon, due to the 15 feed mechanism; in an opposite direction to the movement of the sleeve M, the friction connection between the sleeve and the ribbon reel serving merely to keep the proper tension on the ribbon, this tension on the 20 ribbon being renewed after each impression so that it will always be tight. Supposing the ribbon to be moving from left to right; when all the ribbon has been wound on the spool X, an automatic reversal of the ribbon mechanism takes place, and the ribbon then begins to unwind, and having fully 25 unwound, it then is rewound on the spool X, but this time in the opposite direction, and then when the spool becomes full at this 30 winding, a reversing action of the mechanism takes place, and the operation is repeated. From the above it will be understood that the reversing actions take place immediately after the predetermined or 35 substantially entire amount of ribbon has been wound on the spool, then unwinding begins, and when the ribbon has been fully unwound, the spool continues to rotate in the same direction to give an opposite rewind to the ribbon, and this movement is continued until the spool is again filled, 40 when another reversing action takes place.

It will be observed that the printing plates are moved by the feed chain so as to slide 45 upon and be guided by parts of the machine table. Fig. 5 indicates the guideway for the plates, made up of the grooves c, c', and an overhanging guard plate c''. The raised portion between the grooves serves to afford 50 a rest for the main body of the plate. The projections on the chain C engage the depressed edge of the plate.

I have provided means whereby the paper sheets to be printed may be fed automatically, and for performing this automatic feed I utilize the up and down movement of the yoke 6 which carries the impression pad 8. This feed mechanism comprises a gage 55 plate 16' carried adjustably by its stem 17 clamped in a socket 18 of a plate or bracket 19, which is held by a pin 20 to the top of the machine frame, Figs. 23-25. This plate 60 19 has a boss 21 at one end into which the threaded end of a rod 22 is screwed, the said 65 rod passing through a boss 23 at the other

end of the plate 19. In this latter boss a sleeve 24 is fixed by a screw 25', and over this sleeve is adapted to slide a paper feed carriage or bracket 25 having an arm 26 which carries a pair of rollers 27, each having a rubber periphery 28, the said rollers turning on pins 29 supported on the arm 26. The rollers have portions 30 toothed on their front faces adjacent the arm 26 to be engaged by paws 31 mounted in the arm 26 and pressed forward by springs 32. These pawls prevent rotation of the feed rolls 27 in one direction, while permitting them rotation in the other direction. The sleeve 24 extends only part way into the cylindrical portion or sleeve part of the carriage 25 to the point indicated at 24'. The said sleeve contains a spring which is attached thereto at the point 33, and said spring also extends through the cylindrical or sleeve portion of the paper feed carriage 25, and is attached thereto at the point 34. The carriage is operated along the sleeve by a slip joint link connection consisting of the rod 35 extending into the hollow section 36, which is pivotally connected with the yoke 6, the rod 35 being pivoted to an ear on the carriage sleeve 25. The papers to be fed are placed in position against the gage 16', as indicated by the dotted lines x, which thus serves the purpose of a stop and of a guide for the movement of the paper to keep it straight, and this stop also regulates the amount of margin. This stop is adjustable in relation to the plate 19, its stem being clamped, as 95 above mentioned, by means of the screw 37. As the yoke moves downwardly to bring the impression pad 8 into action for making the impression from the printing plate and through the ribbon, the link connections 35, 36, will move the paper feed carriage 25 toward the left, Figs. 23 and 24, the rolls 27 being free to rotate when the carriage is moved in this direction. The said rolls are thus brought into contact with the sheet 110 which is next to be fed into position beneath the impression pad, and in this action or movement of the carriage toward the left, the spring within the carriage and the sleeve 24 will be compressed, so that after the impression has been made upon the paper already in position beneath the pad, and the said pad, together with the yoke, rises, the spring will move the carriage 25 toward the right, and as the rolls in this movement are 115 held from rotation, they will draw the paper sheet from the gage or stop 16' and feed it beneath the pad 8, and into position to be printed upon. The spring within the sleeve and the carriage also serves as a torsion 120 spring to keep the carriage, with its arm 26, pressed downwardly, so that the feed rollers will make proper contact with the sheet to be fed.

In order to adjust the amount of feed, a 125

collar 38 is fixed on the screw rod 22, and adapted to form a stop against which the end of the paper carriage 25 will strike on its movement toward the right. By turning the screw rod in the bearing 21, the collar 38 may be set at different points in relation to the stroke of the carriage so as to limit the movement of the same on its return to the right. This collar is graduated, and a portion of the frame or bracket 19 is also graduated, so that accurate adjustment of the collar may be secured. By reason of the slip joint connection between the yoke and the paper feeding bracket or carriage, the said bracket may be stopped by the collar 38 at different points in relation to the upper stroke of the yoke 6; that is to say, the bracket may be arrested before the yoke completes its upward stroke. This is of importance, because the amount of movement of the paper feed bracket is thus made independent of the up-stroke of the yoke or the operating foot lever, which is not always uniform.

By reference to Fig. 24 it will be observed that the center U' at which the slip joint link is pivoted to the yoke, describes an arc of movement indicated by the dotted lines Z, and by reason of the arrangement of the paper feeding carriage and the connections described, the outward movement of the carriage is completed before the yoke 6 has reached its lowest position. In other words, after the yoke has moved part way down, the point U' will move substantially in a vertical direction as it is approaching the horizontal plane of the lower pivot of the link 7, and during this substantially vertical movement, no material movement will be imparted to the paper carriage or bracket. In this way the measured stroke of the feed attachment is, in a large measure, independent of the amount of downward movement of the foot lever, which may vary somewhat. Furthermore, by the arrangement described, the pad is allowed to lift from making the impression before the paper is moved.

Reverting to the arrangement by which duplicating, triplicating and repeating of the impressions may be secured, it will be understood that these actions may be effected through the mechanism above described relating to the ring a' and the pawls G' and H'. It will be observed that if one of these pawls is thrown in for making one impression, it has then turned the ring so that the plate moving mechanism is rendered inoperative, and it will be apparent also that if the pawl is thrown out of action at this point, the plate moving mechanism will remain inoperative. All the pawls will then be out of action, and no movement of the plate feeding chain will be effected, and repeating may be done. When it is desired to

again set the plate moving mechanism in motion, the duplicating pawl is again thrown in for one impression, or the triplicating pawl for two impressions, and again thrown out.

In Fig. 26 is shown a cover plate Z which has an opening Z' through its center, the said plate acting as a shield to keep the ribbon away from the paper being printed upon.

For holding the tray f at its upper end in relation to the stacker chute, I employ a plate f² secured to the stacker chute and having a lip or overhanging portion f³ below and back of which the bottom plate of the tray is thrust, as indicated in Figs. 4 and 4^a. Sheets 3 and 7. The depending main part of this plate f² fits in between the sides f' of the tray, and thus centers the tray for the opening or spreading of its detent springs f². The ends of these spring detents, as the tray is thrust upwardly in the direction of the arrow x, Fig. 4, slide upon the inclines f⁵ of the stacker chute casting, and they are thus spread apart, as indicated in Fig. 4^a remaining in this position while the printing plates are being delivered to and stacked in the tray, and thus offering no obstruction to the stacking of the plates. In placing the tray in position, it is thrust upwardly in the inclined position of Fig. 4, and when fully up, it is swung forward at its lower end and then pulled down until it is caught and held by the clips f⁶.

The same trays are used in the feed chute at the right of the machine, Fig. 1, from which the feed chain takes the printing plates to feed them to the impression pad. This plate feed chute or hopper consists of two side standards 39, 39', of angle iron form, having inclines 40 at their lower ends, which, when the tray is forced downwardly, receives the beveled heads of the spring detents f² and spreads said detents apart, so that the printing plates can move downwardly without being obstructed by said detents, as indicated in Figs. 27, 28 and 29. The tray is held in position at the feed chute by a detent 41 engaging the upper end thereof, and at its lower end the tray is directed to place and held by the inclines 42 at the lower parts of the standards of the chute. The tray is first thrust downwardly to engage its seat in the feed chute or standards, as indicated in Fig. 30, which action spreads the spring detents, and then the tray is swung forward at the upper end until it is engaged by the detent which holds it in position. In moving forward into position the tray passes between the lugs 43 which also serve to hold the tray against displacement. Fig. 27 also illustrates the arrangement for taking the plates one by one from under the pile. At the lower part of the standard 39' a stop 44 is fixed or secured which holds back the second printing plate 130

from the bottom while the lowest plate is being engaged by the dog on the feed chain, and is being fed thereby to the impression pad. When the lowermost plate is removed,

5 the next one above it drops down ready to be engaged by the next dog on the chain. The bottom of the standard is recessed at 45 adjacent the stop so that the driving dog may pass fully under the plate without jamming should it lose its hold on the edge of the plate. This prevents the dog from wedging under the plates by allowing the plate to lift on the side where the dogs engage.

It will be seen that the trays for holding 15 the plates having the detent or holding means at both ends are used in such manner that at the receiving end of the feeder the plates are discharged from one end of the tray, that is, the lower end, and are taken by 20 the feeder to be carried to the impression means, and at the other end of the feeder the tray receives the plates at its upper end. The tray, therefore, is formed with a 25 throughway for the passage of the plates, one end being the receiving end and the other the discharge end, and they are used so that the plates are discharged in the same 30 relation as they are received, and any tray can be used at either the feeding in end or the discharge end of the feeder. In other words, at the discharge end of the feeder the plates are received with their impression surfaces uppermost, and when this tray full 35 of plates is to be again used in this machine, it is positioned at the feeding in end of the machine, and the plates are delivered from the discharge end of the tray with their impression surfaces uppermost ready to be taken by the feeder chain and carried in this 40 position to the impression means.

It will be observed that the detents are combined with the plate holding tray to move laterally in respect thereto, and at 45 each end thereof, and at points above the bottom of the tray so that the address plates set upon edge in the tray will be engaged and held by these detents at a point intermediate of their height. The address plates are fed into the tray and after the tray is 50 filled it can be removed from the machine, the detents at the opposite ends of the tray holding the plates in position and when these plates are to be again used the tray is set in the machine with its other end in position for the delivery of the plates therefrom, and in the same order in which they 55 were received, the first plate delivered into the tray at one end having been moved through and held at the opposite end of the tray to be the first one delivered therefrom, and by this the order in which the plates are arranged is maintained. By having the 60 detents at both ends of the tray, one end can be the receiving end and the other the discharge end, and in placing the tray in either

its receiving or discharging position the detents at that end will be pressed back automatically by contact with the inclines on the supports to allow the plates to be moved past these detents.

I claim as my invention:—

1. In combination a reciprocatory impression member, an endless carrier for printing plates consisting of the endless chain and wheels therefor, a driving member for the 75 said carrier consisting of the drum and the pawl and ratchet, connections for operating the impression member, and connections connected with the drum for setting the driving member ready to act when the impression member is advanced, said driving member acting when the impression member retracts.

2. In combination, a reciprocatory impression member, a feeder for the address plate consisting of an endless chain and supporting wheels therefor, a spring and a pawl and ratchet, for operating the feeder, a drum carrying the pawl, a chain connected with the drum, a connection between the spring and drum, a connection for operating the impression member and means for operating the last mentioned chain to turn the drum and strain the spring, substantially as described.

3. In combination a reciprocatory impression member, an endless feeder for the printing plates, a drum, a pawl carried thereby, a shaft on which the drum is supported, a ratchet on the shaft, a spring connected with the drum, a connection for advancing the 100 impression member and a connection for setting the pawl and the spring in position and condition to act to move the endless feeder to feed the plates when the impression member retracts, substantially as described.

4. In combination an impression member, a chain or belt for feeding the printing plates, a drive shaft, a ratchet thereon, a drum turning loosely on the shaft, a pawl carried by the drum, a spring with a connection to the drum to wind thereon, a flexible connection for turning the drum and rendering the spring tense, and a connection for operating the impression member, substantially as described.

5. In combination a table an impression member an arm reaching over the table and having a vertical portion, an operating lever connected with the lower part of the vertical portion, and a link pivotally connected with the upper part and with the frame, substantially as described.

6. In combination, an impression member, a printing plate feed including a feed pawl with connections for operating the same, including a pawl carrier, a cam ring for controlling the pawl mounted on the pawl carrier, and having a tooth or notch, and a detent for engaging the said tooth when the pawl carrier, together with the ring, rotates

to exert control of the pawl, substantially as described.

7. In combination an impression member, a printing plate feed, comprising a drum, a pawl carried thereby, a ratchet, a ring mov- 5 ably mounted on the drum and having a cam portion for controlling the pawl, and having teeth for duplicating and triplicat- 10 ing, a duplicating detent and a triplicating detent, substantially as described.

8. In a machine of the class described, a table, an impression member in the form of a yoke having one arm reaching over the table and a lower arm, a link connecting the 15 yoke with the frame, and operating means connected with the lower arm including a pivoted lever, substantially as described.

9. In combination an impression member, a table having a guideway for printing 20 plates upon which the plates are supported, and a plate feed consisting of an endless carrier for moving the plates intermittently along the guideway of the table and beneath the impression member, said carrier engag- 25 ing the end of the plate near one side edge only, substantially as described.

10. In combination an impression mem- 30 ber, a feeder for printing plates which have depressed edges, and a guideway for one of said depressed edges, said feeder engaging one only of said depressed edges, substan- tially as described.

11. In combination an impression mem- 35 ber, a feeder for printing plates which have depressed edges, and a guideway along which the plates are moved, the said feeder engaging one only of the said depressed edges, substantially as described.

12. In combination an impression mem- 40 ber, feeder means for plates which have each a depressed marginal portion, a table upon which the raised main part of the plate rests, with a side guide for the depressed margin, and a guard member overhanging 45 the depressed margin, said feeder means engaging the depressed margin of the plate beneath said guard.

13. In combination an impression mem- 50 ber, a feeder for plates which have a central raised portion and a depressed marginal portion with a recess on the under side of the plates and guide grooves for said de- 55 pressed marginal portions, one of the guide grooves having a part overhanging the same, said feeder moving the plates along the guide grooves by engaging one of the de- 60 pressed margins, and while the plates rest with their raised portion upon the table between the guide grooves, substantially as described.

14. In combination an impression mem- 65 ber, a feeder for plates which have a de- pressed marginal portion, and a guide for said depressed marginal portion having a part overhanging the same, said feeder en-

gaging with the depressed margin of the plate beneath said overhanging portion, sub- stantially as described.

15. In combination an impression mem- 70 ber, a feeder for the printing plates, a stacker chute pivotally mounted at its upper end and depending vertically from its pivot support, and a tray removably held by the said stacker chute to receive the plates, said chute, when turned on its pivot, permitting 75 the ready removal of the tray, substantially as described.

16. In combination an impression mem- 80 ber, a printing plate feeder, a stacker chute, a screw journaled in and carried by said chute, a bottom or rest for the plates mounted on and depressed step by step by said screw, and the gearing for turning the screw, said stacker chute being pivoted axially of one of the gears, substantially as 85 described.

17. In combination, an impression mem- 90 ber, an inking ribbon movement including a ribbon spool at one end of the ribbon ar- ranged in fixed bearings, and a reel at the other end also arranged in fixed bearings, means for operating the ribbon spool, a plate feeder with connections for operating the same intermittently, and a connection between the plate feeder and the fixed reel 95 for operating the latter intermittently, sub- stantially as described.

18. In combination a reciprocatory im- 100 pression member, a ribbon spool, connec- tions between the impression member and spool for driving the latter as the impression member retracts, an intermittent printing plate feeder with connections for operating the same, a ribbon reel, connections between 105 said plate feeder and ribbon reel tending to operate the latter, said connections includ- ing a friction member which will drive the reel in one direction when the spool un- winds, and will permit the reel to turn in the opposite direction when the spool winds, 110 substantially as described.

19. In combination printing plates, im- 115 pression means, a hopper or chute for the plates, a transporter having projections to engage the plates at one side thereof, said chute having a stop to engage the plates at the side opposite that where the projections engage, and having a recess alongside the said stop, substantially as described.

20. In combination an impression mem- 120 ber, an intermittent printing plate feed, said impression member consisting of an upper arm reaching over the table, and a lower arm extending under the table, with a ver- 125 tically extending portion connecting the said arms, a link connected with the upper part of the impression member, and a piv- oted lever connected with the lower arm of said impression member, substantially as described.

21. In combination an impression member, an intermittent printing plate feed, a clutch with means for driving the same, said clutch being connected with the printing plate feed, a cam ring for controlling said clutch, and a stationary pawl for controlling the cam ring, substantially as described.
22. In combination an impression member, an intermittent printing plate feed, a clutch with means for driving the same, said clutch being connected with the printing plate feed, a cam ring for controlling said clutch and carried thereby, and a stationary pawl for controlling the cam ring, substantially as described.
23. In combination an impression member, an intermittent printing plate feed, an oscillating clutch with means for driving the same, said clutch being connected with the printing plate feed, a cam ring for controlling said clutch, and a stationary pawl for controlling the cam ring, substantially as described.
24. In combination an impression member, an intermittent plate feed, a clutch connected with the plate feed for moving the same, an adjustable controller for said clutch mounted on and moving with a part of the clutch and means for holding the controller in adjusted position while the clutch member continues its movement, substantially as described.
25. In combination an impression member, an intermittent printing plate feed, a clutch with a connection to the printing plate feed for operating the same, a cam ring carried by a part of the clutch for controlling the clutch, and means for controlling the cam ring, substantially as described.
26. In combination, an impression member, an intermittent printing plate feed, a clutch having a connection to the printing plate feed for operating the same, a cam mounted on the clutch to be frictionally carried thereby, and arranged to control the clutch, and means for controlling the cam, substantially as described.
27. In combination, an impression member, an intermittent printing plate feed, a clutch having a connection to the printing plate feed for operating the same, a cam mounted on the clutch to be frictionally carried thereby, and arranged to control the clutch and means for controlling the cam, said controlling means consisting of a pawl or pawls mounted on a fixed point to engage the cam, substantially as described.
28. In combination with a stacker support, a tray having a spring detent movable laterally in respect thereto and above its bottom to engage address plates set up on edge therein, said stacker support having an incline for moving the detent when the tray is placed in connection with said support, substantially as described.
29. In combination with a stacker support, a tray having a detent at each side movable laterally and above its bottom to engage address plates set up on edge therein, said stacker support having means for spreading the detents when the tray is placed in position thereon, substantially as described.
30. In combination with a stacker support, a tray having detent means at its ends, a guide on the support for centering and holding the tray when moved upwardly, and means on the support for retracting the detent means, substantially as described.
31. In combination with a stacker support, a tray having detent means at its end, said tray being movable upwardly and downwardly in seating it, means on the stacker support for retracting the detent means when the tray is moved upwardly, and means for engaging the tray when moved downwardly to hold the same in relation to the support, substantially as described.
32. In combination in apparatus of the class described, for printing from address plates, trays having pairs of detent means at opposite ends, a support for the trays with means for retracting the pairs of detent means at one end thereof when the trays are held by the said support, to thereby permit the discharge of the address plates from the trays, and a second support for the trays having means for retracting the pairs of detent means at the other ends thereof to allow the address plates to be deposited in the trays.
33. In combination in a machine of the class described, a tray having detent means and adapted to be held with one end above the other to receive or deliver address plates, a support having means for engaging the detent at the lower end of the tray for the discharge of the articles therefrom, said means serving to retract the detent means, and a second support for the trays having means for retracting the detent means at the upper end of the tray to allow the plates to be fed into the said tray, substantially as described.
34. In combination in a machine of the class described, a support at one end thereof, a tray having detents at its opposite ends and adapted to be held with one end above the other to receive or deliver address plates, said support having means to retract the detent at the lower end of the tray for the discharge of the articles, and a second support having means at its upper end for retracting the detent at the upper end of the tray for the feeding in of the articles, substantially as described.
35. In combination in a machine of the

class described, an impression member, a feeder for printing plates, a tray at one end of the feeder having a detent with means on the frame for retracting the said detent to allow the plates to be discharged from the tray onto the feeder, and a tray at the other end of the feeder having a detent with means on the frame for retracting the said detent to allow the plates to be fed into the tray,

5 10 substantially as described.

36. In combination in a machine of the class described, an impression member, a feeder for printing plates, means for removably holding a tray at one end of the feeder 15 to supply the plates thereto, and means for holding a tray removably at the other end of the feeder to allow the plates to be fed into the same, said trays having means at each end for holding plates therein, said 20 means being movable to permit the plates to pass by, substantially as described.

37. In combination in a machine of the class described, an impression member, a feeder for printing plates, a holder for a removable tray at each end of the feeder, and a tray carrying thereon detent means at each end, and means at the holders for retracting the detent means when the tray is placed in position at said holders, substantially as described.

38. In apparatus of the class described, impression means, a plate feeder, and a tray having a through way from end to end for the passage of the plates therethrough in a certain order, and means for holding the trays at the receiving and discharge points of the feeder, said tray having at each end releasable holding means for the plates operated by contact thereof with the holding 35 40 means when set in position thereon, substantially as described.

39. In apparatus of the class described, impression means, a plate feeder, a pair of trays each having retaining means at each end for the plates, and holders for the trays 45 one at the receiving point of the feeder and the other at the discharge end of said feeder, with means for releasing the retaining means of the discharge end of the tray at the receiving point of the feeder and for releasing the retaining means at the receiving end of the tray at the discharge point of the feeder, substantially as described.

40. In combination in apparatus of the class described, impression means, an address plate holder, an endless feeder for the address plates, a pawl and ratchet wheel drive for the feeder to operate it intermittently, a ribbon reel with a connection from the pawl and ratchet wheel drive of the 60 endless feeder for operating said ribbon reel, a ribbon spool and a connection between the impression means and the ribbon spool for operating the same, substantially as described.

41. In combination a plate feeder, an impression member, a ribbon reel for one end of the ribbon, a ribbon spool for the other end of the ribbon, means for operating the plate feeder and impression member intermittently, an operating connection between the ribbon reel and the plate feed, and an operating connection between the impression member and the spool, substantially as 70 75 described.

In testimony whereof, I affix my signature in presence of two witnesses.

ULYSSES G. LEE.
